SUPERHEATER

Charles F. Krauss, Ambler, Pa.

Application February 8, 1934, Serial No. 710,233

2 Claims. (Cl. 122—462)

This invention relates generally to locomotive superheaters of the fire tube type and more particularly to an improved combination of superheater tube units adapted to offer minimum resistance to the steam flow consistent with obtaining a relatively high degree of superheat.

A great many superheater arrangements have heretofore been proposed and developed for locomotives to obtain a high degree of superheat, but certain of these developments have been carried so far that the value of the increase in superheat is outweighed or not justified by the drop in pressure caused by the superheater tubes. Certain prior patents have recognized the disadvantages of excessive friction and have attempted to overcome the same while still maintaining an acceptable degree of superheat, but these prior arrangements have not been fully successful.

It is one object of my invention to provide an improved combination of superheater tube units so similarly constructed and uniformly applied to substantially the entire group of boiler flues as to obtain a minimum drop in pressure consistent with a high degree of superheat.

25 A further object is to accomplish the foregoing results by providing each of the uniformly distributed units with what is herein termed a maximum superheat run and a minimum superheat by-pass run, these runs being commonly connected to pipes leading to and from the saturated and superheated steam chambers of the superheater header.

Other objects and advantages will be more apparent to those skilled in the art from the following description of the accompanying drawings in which:

Fig. 1 is a fragmentary longitudinal section of a locomotive boiler;

Fig. 2 is an end elevation of Fig. 1 looked at in the direction of the arrow *a*, Fig. 1;

Fig. 3 is a side elevation of one of the superheater tube units;

Fig. 4 is a bottom plan view of the unit looking up at the bottom of Fig. 3;

Fig. 5 is an end elevation of Fig. 3 viewed in the direction of the arrow *b*;

Fig. 6 is a perspective of the tube unit.

In the illustrated embodiment of the invention which is disclosed herein merely for the purpose of showing one specific form among possible others that the invention might take, there is provided in Fig. 1 a locomotive boiler shell generally indicated at 1 having usual flues 2, a front tube plate 3 and saturated steam pipe 4 connected in a usual manner with any desired form

of superheater header generally indicated at 5. This header is located preferably in the smokebox 6 and as the construction of such a header is well-known as is also the case with the remaining locomotive structure, it is not deemed necessary to describe the same in detail.

As shown in Fig. 2 the flues 2 are disposed in staggered relation in the customary manner and the tubes of the superheater units generally indicated at 7, Figs. 3-6, are inserted within the flues 10 from the smokebox. However, in order to obtain my improved results above mentioned together with a uniform quality of superheated steam, each unit is provided with a saturated steam inlet pipe 8 and a superheated steam outlet pipe 9, 15 these pipes being connected with the usual chambers of the superheater header 5. However, it will be noted that inlet pipe 8 communicates with a pipe 10 and a reversely extending pipe 11 to communicate with outlet pipe 9. Pipe 8 also 20 communicates with a pipe 12 and a reversely extending pipe 13, this pipe 13 continuing in series communication through a bend 14 with a pipe 15 and reversely extending pipe 16. Pipe 16 then communicates with pipe 9 in common with 25 pipe 11. As is customary, each pair of pipes 10 and 11, 15 and 16, and 12 and 13 is respectively received in individual flues.

In my improved arrangement all of the superheater tube units are of the type having the three 30 passes generally indicated at 18, 19 and 20 in Fig. 6, the passes 19 and 20 being preferably in superimposed relation whereby the respective passes are triangularly arranged for insertion in triangular groups of flues. These triangular groups 35 are shown in Fig. 2 by the heavy dotted triangular lines 21. It will be noted that the horizontal group of triangles at the elevations *c* have their apexes on the right hand side while the triangles at the alternate elevations *d* have their 40 apexes at the left hand side. When each vertical column of triangles is viewed, it is seen that the triangles are alternately of a left and right hand nature disposed in complementary nested relation. As a result of this arrangement only two 45 groups of superheater tube units are necessary to cover substantially the entire group of flues, except that the inlet and outlet pipes must be of different lengths to accommodate the different elevations of the units. However, it is seen that 50 in so far as the superheater pipes are concerned that the interfitting triangles present a uniform distribution of the superheater tube units 7 which may be generally described as similar even though there are right and left hand groups. Also, as a 55

result of the three pass arrangement as described, it will be observed that the steam flows in series through the passes 19 and 20, Fig. 6, thereby causing maximum superheating of this steam and for that reason this pair of passes is herein referred to as a maximum superheat run, whereas the pass 18 by having only one pair of pipes will not cause the steam flowing therethrough to have the same degree of superheat as in the other run but will nevertheless have at least a certain minimum superheat and this will be accompanied by less frictional resistance than in the other pass. Due to this differential frictional resistance, the steam will not divide evenly between pipes 10 and 12 at the juncture 22, but more steam will flow through pipe 10 thus causing the run of pipes 10 and 11 to serve somewhat in the nature of a bypass for the other run of pipes 19 and 20. Hence pipes 10 and 11, which have minimum superheat but function as a bypass, are herein termed as a minimum superheat bypass run.

As a result of my improved arrangement, both functional and structural difficulties and objections to prior superheating arrangements are overcome because by uniformly distributing the maximum superheat runs and bypass runs over substantially the entire group of flues, excessive pressure drop is minimized consistent with maintaining a very substantial quality of superheat. It will be noted that the bypass run 12 is preferably of somewhat greater length than the other runs, thereby permitting a desired degree of minimum superheat to be obtained without materially increasing the friction through the bypass run as no additional bends are included.

It will of course be understood by those skilled in the art that various changes may be made in the details of construction and arrangement of parts without departing from the spirit of the invention as set forth in the appended claims.

I claim:

1. The combination with a locomotive boiler provided with a plurality of flues disposed in staggered relation comprising, a superheater header, substantially similar superheating tube units uniformly disposed in substantially all flues, each unit having a triangular arrangement of three passes two of which are disposed in series to form a maximum superheat run while the third pass forms a minimum superheat bypass run, said runs having a common saturated steam inlet pipe and a common superheat outlet pipe for connection to said superheater header and each pass of any one unit being disposed in its own individual flue of a triangular group of flues, the superheater tube units for parallel rows of flues being alternately arranged in left and right hand positions and said arrangement extending over substantially the entire group of similar rows of flues.

2. The combination with a locomotive boiler provided with a plurality of flues disposed in staggered relation comprising, a superheater header, substantially similar superheating tube units uniformly disposed in substantially all flues whereby the units are arranged in vertical columns, each unit having a triangular arrangement of three passes two of which are disposed in series to form a maximum superheat run while the third pass forms a minimum superheat bypass run, said runs having a common saturated steam inlet pipe and a common superheat outlet pipe for connection to said superheater header and each pass of any one unit being disposed in its own individual flue of a triangular group of flues, each vertical column of the triangular superheater tube units having the units alternately reversely arranged in complementary nested relation.

CHARLES F. KRAUSS. 40
